(57) **CLAIM**

The ornamental design for a wrap dispenser, as shown and described.

DESCRIPTION

FIG. 1 is a front perspective view of a wrap dispenser showing my design.

FIG. 2 is a bottom rear perspective view of the wrap dispenser.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a sectional view of the wrap dispenser; and,

FIG. 10 is an enlarged view of an area labeled 10 in FIG. 1. The broken lines depict portions of the wrap dispenser that form no part of the claimed design. The dash-dot broken lines in the figures are demarcating enlarged areas and form no part of the claimed design.
